SEWING MACHINE CABINET

Aubrey M. Chisholm, Box 91, Woodrow,
Saskatchewan, Canada

Filed Apr. 4, 1969, Ser. No. 16,578

Term of patent 14 years

Int. Cl. D6—01

U.S. Cl. D33—12

FIG. 1 is a right front perspective view of my sewing machine cabinet.

FIG. 2 is a left end elevational view of same.

FIG. 3 is a right end elevational view of same.

FIG. 4 is a top plan view of the same with its right and left leaves extended.

FIG. 5 is a fragmentary right end elevational view showing my tiltable spool rack partially swung open.

The back of the cabinet is conventionally plain and unornamented.

I claim:

The ornamental design for a sewing machine cabinet, as shown and described.
